COMBINATION HEATER AND AIR CONDITIONER

Duane H. Williams, 812 Ellenberger Parkway,
Indianapolis, Ind.

Filed Apr. 30, 1964, Ser. No. 79,754

Term of patent 14 years

(Cl. D81—19)

Fig. 1.

Fig. 2.

Fig. 3.

Fig. 4.

FIG. 1 is a front elevation view of the combination heater and air conditioner showing my new design.

FIG. 2 is a rear elevation view thereof.

FIG. 3 is a side elevation of the right side thereof as viewed in FIG. 1.

FIG. 4 is a top plan view thereof.

The side not shown is a mirror image of the side shown. The bottom not shown is plain and unornamented.

The dominant features of my design reside in the portions shown in full lines, which portions are characterized by the arrangement of the grill units in association with the louvered portions intermediate thereof, as seen at the rear in FIG. 2.

I claim:

The ornamental design for a combination heater and air conditioner, as shown and described.
